[57] CLAIM

The ornamental design for a radiant stove heating element, as shown and described.

DESCRIPTION

FIG. 1 is a top plan view of a first embodiment of the radiant stove heating element showing my new design, the bottom being a mirror-image thereof;

FIG. 2 is a front view thereof;

FIG. 3 is a rear view thereof;

FIG. 4 is a left side view thereof;

FIG. 5 is a right side view thereof;

FIG. 6 is a top plan view of a second embodiment of my design, the bottom being a mirror-image thereof;

FIG. 7 is a front view thereof;

FIG. 8 is a rear view thereof;

FIG. 9 is a left side view thereof; and,

FIG. 10 is a right side view thereof.
